FAUCET FOR GARDEN HOSE OR THE LIKE

Carl R. Lindberg, Los Gatos, Calif.

Application May 31, 1950, Serial No. 10,265

Term of patent 14 years

(Cl. D91—3)

To all whom it may concern:

Be it known that I, Carl R. Lindberg, a citizen of the United States, residing at Los Gatos, in the county of Santa Clara and State of California, have invented a new, original, and ornamental Design for a Faucet for Garden Hose or the like, of which the following is a specification, reference being had to the accompanying drawing, forming a part thereof.

In the drawing:

Fig. 1 is a side view of a faucet for garden hose or the like, showing my new design.

Fig. 2 is an end view of Fig. 1 as seen from the left side thereof.

Fig. 3 is an end view of Fig. 1 as seen from the right side thereof.

I claim:

The ornamental design for a faucet for garden hose or the like, as shown.
